UNITED STATES PATENT OFFICE.

CHARLES CAREY MANKER, OF OKLAHOMA, OKLAHOMA, ASSIGNOR OF ONE-HALF TO
MURRAY J. MORLEY, OF PITTSBURGH, PENNSYLVANIA.

GAS-RADIATOR.

1,343,634.

Specification of Letters Patent. Patented June 15, 1920.

Application filed July 20, 1917. Serial No. 181,746.

To all whom it may concern:

Be it known that I, CHARLES C. MANKER, a citizen of the United States, and a resident of Oklahoma city, in the county of 5 Oklahoma and State of Oklahoma, have invented a new and Improved Gas-Radiator, of which the following is a full, clear, and exact description.

This invention relates to heating means 10 and particularly to an improved gas heating radiator, and has for its object the provision of certain new and novel features to increase the efficiency thereof and economy of operation, as hereinafter more fully set 15 forth and pointed out in the claims.

In the accompanying drawing:

Figure 1 is a side view of a radiator with an embodiment of the invention applied thereto, certain parts being broken away for 20 better illustrating the construction.

Fig. 2 is an enlarged fragmentary sectional view through the air mixer and associated parts shown in Fig. 1.

Referring to the accompanying drawing 25 by numerals, 1 indicates a radiator of usual construction, provided with a lower passageway 2 and an upper passageway 3 whereby all of the sections of the radiator are in communication. A pipe 4 is passed through 30 the opening in the lug 5 and is threaded in the opening formed in lug 6, said pipe being provided with a plurality of apertures 7 opening into the respective sections 8 of the radiator 1. A cap 9 is threaded on to 35 the free end of the pipe 4 while a cap 10 is threaded on to the gas intake end shown in Fig. 1, said caps rigidly holding the pipe in position and also acting as an anchor bolt for holding the sections 8 together. 40 Cap 10 is provided with a plurality of air inlet openings 11 which provide auxiliary air for the air mixer 12. In addition to this supplying of auxiliary air, apertures 13 and 14 from the end sections 8 of radiator 1 supply air to points adjacent the exterior of pipe 4. Preferably air openings 45 15 are also provided in the bottom of the sections 8 and air openings 16 in the top.

The mixer 12 may be of any desired construction, the same being formed with a 50 burner 17, which burner may be merely a tube covered with a wire mesh 18 so that the gas may be projected for substantially the full length of tube 4, said gas being ignited and providing a flame which will heat 55

the tube 4, said tube being formed of iron or other suitable material to withstand this heat and which will radiate the heat to the air in the sections 8 and eventually to said sections, while said sections in turn radiate 60 the heat to the surrounding atmosphere.

In order to provide the mixer 12 with gas a suitable supply may be provided through the supply pipe 19 shown in Fig. 1, said supply pipe discharging into a valve 20 controlled by the thermostat 21 so as to vary the amount of gas passing into the pipe 22. Pipe 22 is connected through a fitting 23 to the air mixer 12, a suitable hand operated valve 24 being interposed in pipe 22 70 for manually controlling the gas or for entirely turning off the same. The construction of the thermostatic valve 20 and the thermostat 21 may be of any kind. Preferably it is such as may be adjusted so that 75 the thermostat may be caused to maintain a certain flow of gas whereby a certain heat will be produced. During the operation of the device the heat will naturally rise and in order to provide a better distribution 80 thereof and to catch any small particles of combustion that have not been consumed, an inverted dish-shaped member 25 is provided and held in position by suitable supports 26. 85

What I claim is:

1. A gas heated radiator, comprising a plurality of hollow sections having adjacent their upper and lower ends passageways establishing communications between the 90 sections and each provided with perforations in its top and bottom, the end sections having internally threaded annular flanges at the lower passageway, a burner tube disposed in the lower passageway and having 95 perforations opening into each of the sections, the ends of the tube being screw threaded and screwing into the threaded flanges of the end sections, with the threaded ends projecting beyond the said end sections, 100 caps screwing on the ends of the tube, one of the caps having an opening in its end, a burner extending through the opening of the cap into the burner tube, and a plate like member secured to the upper ends of the 105 end sections in spaced relation to the said sections.

2. A gas heated radiator comprising a radiator body having a plurality of hollow sections secured together and each section 110

- being provided with perforations at its top and at its bottom for the passage of air, and said body portion having an upper and a lower passageway for affording communication between the sections, a tube disposed in said lower passageway and being provided with perforations registering with the various sections, a burner extending into one end of said tube for providing a flame 10 in the tube, and an inverted non-perforated dish-shaped plate secured above the upper ends of said sections in the path of the products of combustion passing through the perforations.
15. 3. A gas heated radiator comprising a radiator body, having a plurality of vertically disposed hollow sections secured to-

gether and each section being divided into perforations in its top and in its bottom for the passage of air, said body portion 20 having an upper and a lower laterally extending passageway for affording communication between the sections, a tube disposed in said lower passageway and being provided with perforations registering with the 25 sections, a burner extending in one end of said tube for providing a flame in the tube, and an inverted non-perforated dish-shaped plate secured to and spaced from the upper end of said sections in the path of the products of combustion passing through said 30 perforations.

CHARLES CAREY MANKER.
